Inventor:
DEAR TUNG HOY

E. Bunker Atty.

UNITED STATES PATENT OFFICE.

DEAR TUNG HOY, OF CHICAGO, ILLINOIS.

GRINDING APPARATUS.

Application filed December 28, 1927. Serial No. 243,159.

My invention relates to a grinding machine, and it has more particular reference to a grinder that is actuated hydraulically through the medium of the usual normal pressure maintained in city service pipes.

Primarily, my invention has for its object the provision of a grinder that is of reduced dimensions which permits its storage in a small space and its ready installation upon a tap or faucet in a kitchen-sink and other convenient places where service water outlets are found. Another object resides in providing a grinder that is made from simple parts, and which is so assembled that there is little or nothing to get out of order. In connection with the actuation of the grinder element or stone, I have provided a novel arrangement for assembling the same so that it may be readily replaced by persons unskilled in the use of tools, and I have also provided a counter-balanced governor that may be thrown into action whenever the stone is to be given heavy service, as for example, when grinding large tools. The disposition of the water discharge element is such that the surging stream will splash against the stone in order to maintain the same in moist condition while in use and prevent heating. My apparatus is very compact and it may be readily carried by carpenters, plumbers, and other mechanics, in their tool-chests or kits where it is always ready for use. Other objects of my invention reside in providing a grinding apparatus that is novel and simple in construction, dependable in operation, may be readily taken apart for replacement or repair, and is economical to manufacture so that it may be offered to the retail trade at a moderate price.

I prefer to carry out my invention, and to accomplish the numerous objects thereof, in substantially the manner hereinafter fully described and as more particularly pointed out in the claims, reference herein made to the accompanying drawings that are a part 45 of this specification.

In the drawings:—

Figure 1 is an elevation of my grinder, looking at the front edge thereof with a portion of the grinding wheel and mounting 50 broken away.

Figure 2 is a sectional view showing the turbine or water-wheel construction, the view being taken on line 2—2 of Figure 1 and looking in the direction of the arrows.

Figure 3 is a vertical side elevation of the 55 grinder apparatus illustrating the details of the counter-balance governor.

Figure 4 is a top view of a fragmentary portion of the apparatus showing details of the tool-holder and arm. 60

The drawings illustrate a typical or preferred manner of practicing my invention, and are more or less schematic for the purpose of disclosing the principles involved. In these drawings I have employed similar 65 reference characters to designate like parts wherever they appear throughout the several views.

The housing or casing in which the turbine water-wheel is enclosed consists of a cylindrical shell 5, one side wall 6 of which is preferably formed integrally therewith, while the opposite side wall 7 is in the form of a metal plate of disk shape that is removably secured to the open side of the casing by 70 means of screws 8. At a suitable upper portion of the casing there is an inlet stub 9 having a small bore 10 that communicates obliquely or tangentially with the interior of the casing and at its outer end the stub is provided with a swiveled coupling 11 of the well-known type to permit the apparatus being readily attached to or detached from the service tap or faucet through which water is supplied for domestic and other uses. The lower segment of the casing has an outlet stub 12 that is made by turning the cylindrical wall 75 of the casing outwardly and providing extensions upon the side walls as shown. 80

The side walls 6 and 7 are apertured to receive a rotatable spindle or shaft 13 that is mounted in anti-friction or ball-bearing units 14 and 15 positioned upon the exteriors of the walls so as to permit the easy rotation of said spindle. The ends of the spindle project 90 beyond these bearings and the end that extends through the wall 6 carries the grinding wheel or stone 16 which is of an annular or ringlike construction so that it is unnecessary to use a solid stone as is the usual practice, while the portion of the spindle within the casing has a turbine or water-wheel mounted thereon. This power element consists of a hub 17 that is secured to the spindle 13 by means of a key 18, which hub is provided 95 with a plurality of outwardly curved blades 19 that are set in oblique disposition with respect to axis of the spindle and hub. When 100 105

the water is turned on, the blades are driven by the pressure of the water against them and the water is discharged through the lower stub 12 into the sink or other receptacle. In 5 this connection it should be noted that the lower edge of the outlet stub is in a plane slightly above the horizontal plane of the lowest segment of the grind-stone, so that, as the water is emitted through the stub a limited 10 amount thereof will splash against the stone because of its close proximity thereto, thereby keeping the stone moist and avoid heating the same. If desired, in order to insure a positive moistening the stone, a lateral opening 12^a 15 may be made in the stub on the side thereof next to the stone which will discharge a small stream against the stone and maintain it moist so long as the apparatus is in operation.

The annular grind stone 16 is mounted upon 20 the periphery or outer surface of a cylindrical wheel or drum 20 that has a central hub 21 secured to the extended end of a spindle by means of a key or wedge 22 and is maintained against lateral movement or displacement by 25 a pin 23 that extends transversely through the end of the spindle. The drum 20 is connected with the hub by the web or spokes 24 and there is a continuous flange or abutment 40 that extends beyond the periphery of the 30 drum 20 alongside the edge of the grind stone 16 to form a stop for the latter. The grind-stone is maintained in position and against lateral displacement by means of an annular retainer ring 25 that is placed against the side 35 of the stone opposite the flange 24 and is provided with a plurality of lateral lugs or feet that are substantially L-shaped and are connected to the grind-stone mounting structure by means of screws or the like.

40 A tool-rest is provided which consists of a suitably shaped arm 27 that extends across the face of the grind-stone in the manner shown in Figure 1 and intermediate its ends it rests against a cam-shaped fin 28 on the 45 casing wall adjacent the grind-stone. By moving the tool-rest up or down while in contact with the cam the rest may be adjusted toward or away from the operating surface of the grind stone. The tool rest forms a portion 50 of an L-shape extensible bracket that is mounted upon the outer ball-bearing unit and consists of a ring 29 surrounding the ball-bearing unit and held in position by the ball-retainer cup and has an arm 30 projecting 55 radially therefrom alongside the removable side-wall 7 and at its outer end is cooperatively connected to a lateral arm 31 extending from the tool rest proper. These arms overlap each other so that their combined length 60 may be varied whenever desired by releasing the clamping member 32 and making the proper adjustment and then turning back said clamping member to hold the parts in their adjusted position. The clamping member 32 65 passes through the overlapped arms and

screws into any one of a plurality of tapped or threaded sockets 32^a arranged in an arcuate formation in side-wall 7 of the housing.

Whenever it is desired to employ the grinder in heavy service such as grinding 70 large tools, I have provided a counter-balanced governor that may be readily put into operation, and when in use it will perform the function of a fly-wheel. The end of the spindle 13 is provided with a transverse 75 groove 13^a in which there is mounted a pair of movable arms 33. The ends of the arms that are adjacent each other are provided with eyes 34 through which pivotal pins 35 are passed and the outer ends of the arms 80 are provided with ball-shaped weights 36. It will be understood that when the spindle is rotated rapidly the balls, due to centrifugal force will move the arms outwardly to their fullest extent in which position they will be 85 diametrical opposite each other and will be disposed radially to the spindle and at right angles to the axis of rotation thereof. This will assist in creating an increased momentum for the grind-stone so that large tools 90 may be successfully operated upon by the stone. Under ordinary conditions, when grinding knives or small tools the counter-balanced governor need not be used, and at 95 such times the arms may be moved towards each other and secured in position by means of the overlapping segments 37 that curve towards each other from spaced locations on the arms 33 and when the latter have been placed in the desired position the segments 100 may be secured together by the winged clamping element 38 in the manner shown in the drawings.

I have disclosed only a specific manner of carrying out my invention, but it will be obvious to persons skilled in the art that changes or modifications may be made without departing from the principles herein involved. The foregoing detailed description and drawings have been given for clearness for understanding only and no unnecessary limitations should be understood therefrom, but the appended claims should be construed as broadly as permissible in view of the prior art.

What I claim is:—

1. A grinding apparatus comprising a casing, a fluid inlet stub in the upper portion of the casing, an outlet stub at the lower portion of the casing, a rotor actuated by fluid passing through said casing, a spindle to which said rotor is secured, one end of said spindle being extended beyond the casing, and a grinding stone mounted on the extended end of said spindle, the peripheral portion of said stone being positioned adjacent the outlet 120 stub and there being a lateral orifice in the wall of the outlet stub on its side next the stone whereby a portion of the fluid passing through said stub is discharged on said stone.

2. A grinding apparatus comprising a cas- 130

ing, fluid inlet and outlet stubs at upper and lower portions of the casing, a rotor within the casing and actuated by fluid passing through the latter, a spindle on which the 5 rotor is mounted and having its ends extended through said casing, a grinding element mounted on one extended end of said spindle, a pair of weighted arms swingingly mounted on the other end of said spindle and 10 adopted to be centrifugally moved into positions at substantially right angles to the axis of the spindle, whereby to provide a counter-balance during rotation of the spindle, and means for securing said arms 15 against centrifugal movement.

3. A grinding apparatus comprising a cas-

ing, a spindle extended therethrough, a rotor mounted on the spindle within the casing, means for passing fluid through said casing to actuate said rotor, a grinding element on 20 an extended end of said spindle, a tool-rest arm extended across said grinding element, a swinging extensible bracket on the casing to which said arm is connected, and a cam member on the casing against which the arm engages for limiting the adjustment of the arm towards and away from the grinding element. 25

Signed at Chicago, in the county of Cook, and State of Illinois, this 21st day of December, 1927.

DEAR TUNG HOY.
